FIG. 1 is a front view of a computer showing my new design;
FIG. 2 is a rear elevational view thereof;
FIG. 3 is a left side view thereof;
FIG. 4 is a right side view thereof;
FIG. 5 is a top plan view thereof; and,
FIG. 6 is a bottom plan view thereof.

Portions of FIGS. 1–6 that are shown as even broken lines are for illustrative purpose only and form no part of the claimed design. The dot-dash broken lines define, but are not included in, the boundaries of the claimed design.

1 Claim, 4 Drawing Sheets

Matter enclosed in heavy brackets [ ] appears in the original patent, but forms no part of this reissue; matter printed in italics indicates the additions made by reissue.
